UNITED STATES PATENT OFFICE

HENRY SCHOTTENFELS, OF WEST NEW YORK, NEW JERSEY

BRASSIÈRE

Application filed May 23, 1932. Serial No. 612,934.

This invention relates to brassières, and the invention has for its object the provision of an improved construction of this character which will yield readily in response to the movements of the body while avoiding any constriction of the flesh and any irritating or annoying pressures thereon.

An object of the invention is to provide a construction in which the connected straps 10 are yieldable in practically any direction, with the back straps slidably coupled for free sliding movement with respect to one another and in such manner that the several parts of the device can move relatively and unrestrictedly in accompaniment with the natural movements of the body, and further with the shoulder straps slidably connected with the back straps for free play with respect thereto in response to the movements of the shoulders. 20 Another object of the invention is the provision of a novel hook or connector by means of which to couple the elastic back straps for free sliding movement, and it is an important characteristic of this hook coupling that it is made flat or substantially so to lie in plan with the straps connected thereby and thus with the connected straps to rest flatwise against the back of the wearer. The hook coupling is further made so as to facilitate 25 the connection and disconnection of the back straps.

With the foregoing and other objects in view, the invention consists of the novel construction, combination and relative arrangement of parts as hereinafter more specifically described and illustrated in the accompanying drawing, wherein like reference characters denote corresponding parts of the views, and in which:

40 Figure 1 is a perspective view of a brassière made in accordance with my invention, this view showing the article as it appears when looking at the back thereof; and

45 Fig. 2 is a detail view on a larger scale, showing the hook coupling and showing also in dash-dot lines the back straps in sliding engagement therewith.

50 Referring now with more particularity to the accompanying drawing, it will be seen that the article includes the two usual cup

or breast pockets 10, 10 which may be of any suitable shape or design desired, and these pockets at their inner or adjacent ends 13 are suitably connected by elastic straps 11 and 12. The ends of the straps 11 and 12 are secured to the pockets by any suitable securing means such as by lines of stitching 14.

To each of the pockets, at its outer or remote end 15, is secured an elongated loop-like back strap consisting of a single length of elastic material the opposite ends of which are secured by a line or lines of stitching 14. The opposite ends of each back strap are thus secured to the outer end of its pocket in spaced relation so as to provide upper and lower elastic spans 16 and 17. In applying the brassière, these elongated loop-like elastic back straps, thus connected at the outer ends of the pockets, are extended around the sides of the chest, at points below the arms for connection by means of a hook coupling 18 at the middle of the back.

According to an important feature of my improvement, each of the elongated loop-like back straps is connected with the hook coupling 18 for free sliding movement. In the present embodiment, the hook coupling 18 is represented as comprising a substantially flat member having two elongated eyes 19 and 20 separated by a web 21. Said eyes 19 and 20, as best shown in Fig. 2, are of greater length than the width of the back straps which pass through them. In the present embodiment, the eyes 19 and 20 differ in that the former is made so as to be completely surrounded by the material of the flat member, whereas the latter is made at its lower end with an opening 22 in communication with the outer space. Both of the eyes are of such transverse dimension 80 with respect to the thickness of the material of the back straps that the back straps, when applied to the eyes, can have free sliding movement therein.

It will be manifest that the back strap 95 which passes through the eye 19, must be applied thereto before at least one of its ends or terminals is sewed to the pockets. In this way, the coupling member is permanently mounted on one of the back straps. It will 100

be noted that the web 21 is made with a longitudinally tapering edge 23 and a hump 23' which define the inner side of the eye 20, and that the general direction of the taper is 5 towards the passage 22 so that the web narrows towards this passage. It will be further noted that adjacent said passage 22, the web is rounded at 24, exteriorly of the eye 20. Opposite the rounded portion 24, the coupling member is provided with a hook 25 by means of which the passage 22 is narrowed to such extent that it is merely equal to the thickness of the material of the back strap. By reason of this provision, the back 10 strap for the eye 20 must be inserted and removed edgewise through the restricted passage 22; and the tapering and rounded portions 23 and 24 are provided in order to facilitate the application and removal of the 15 back strap edgewise through the restricted passage 22, by the fingers. The hump 23' is located substantially midway the length of the eye 20 and it may project into the eye far enough to contact with a back strap 20 25 cupping the eye. The purpose of the hump is to prevent accidental edgewise shifting of the strap over the hook 25 and hence outwardly through the passage 22, while permitting free sliding movement of the strap 30 in the eye. In view of this special arrangement, the wearer of the article, by moving her arms behind her and just below the shoulders can herself readily apply the back strap to the eye 20 or remove it therefrom. 35

According to another feature of my invention, suitable shoulder straps 26 connect the pockets with the upper spans 16 of the back straps. Each of these shoulder straps is connected at one end to the upper edge of the 40 pocket, and more particularly at a point as 45 27 substantially midway the length of the pocket. At its opposite end, each of the shoulder straps is provided with a loop 28 in which is slidably received the upper span 16 50 of its respective back strap.

The hook coupling may be made of thin sheet metal, of tape, cloth or any suitable material and it will be recognized that by reason of the manner in which the two loop-like 55 back straps are slidably connected therewith, this flat hook coupling will lie in plan with the back straps flatwise therewith against the back of the wearer.

It is characteristic of this invention that 60 the front and back straps yield readily in response to bending and twisting movements of the body and to the relative muscle movements of the chest, back and shoulders, with the back strap sliding freely in the hook coupling, while the shoulder straps have free

sliding movements upon the upper spans of the back straps.

While the invention has been illustrated and described with some degree of particularity, it will be recognized that in practice various changes and alterations may be made therein. It has been sought herein to illustrate only such an embodiment as will suffice to exhibit the character of the invention. Reservation is, therefore, made to the right 70 and privilege of changing the form of the details of construction or otherwise altering the arrangement of parts without departing from the spirit or scope of the invention or the scope of the appended claims. 80

I claim:—

1. A brassière having breast pockets connected at their inner ends by elastic means, elastic back straps extending from the outer ends of the pockets, a hook coupling for the back straps in which the latter have free 85 sliding engagement, and shoulder straps for the pockets having ends slidably engaged with the back straps.

2. A brassière having breast pockets connected at their inner ends by elastic means, shoulder straps each having one end thereof attached to a pocket, elongated loop-like back straps extending from the outer ends of the pockets, sliding connections between the opposite ends of the shoulder straps and the back straps, and a hook coupling between the back straps having sliding connection therewith. 95

3. A brassière having breast pockets connected at their inner ends by elastic means, elastic back straps extending from the outer ends of the pockets, shoulder straps each having one end thereof attached to a pocket, sliding connections between the opposite ends of the shoulder straps and back straps, and a hook coupling for the back straps, formed with loops in which the back straps have sliding engagement, said hook coupling being substantially flat to lie in plan with the 100 back straps flatwise therewith against the back of the wearer. 110

4. A brassière having breast pockets connected at their inner ends by elastic means, shoulder straps extending from the pockets, elongated loop-like back straps extending from the outer ends of the pockets and each having upper and lower spans, sliding connections between the shoulder straps and the upper spans of the back straps, and a hook 115 coupling for the back straps, provided with eyes in which the back straps have independent sliding engagement. 120

5. In a brassière, the combination with connected breast pockets and loop-like back straps connected with the pockets, of means for slidably connecting the back straps, comprising a substantially flat coupling member having individual eyes for the respective back straps, at least one of said eyes being open to 130

provide for the manual detachment of the therewith engaged back strap, and means on the coupling engageable with the back strap to prevent accidental escape of the back strap through the opening.

In testimony that I claim the foregoing as my invention, I have signed my name hereto.

HENRY SCHOTTENFELS.
